Alexander Denes

UNITED STATES PATENT OFFICE.

FRANK KLINGA, OF NEW YORK, N. Y.

TWINE OR CORD CUTTER.

1,203,120.

Specification of Letters Patent. Patented Oct. 31, 1916.

Application filed May 3, 1916. Serial No. 95,146.

To all whom it may concern:

Be it known that I, FRANK KLINGA, a subject of the King of Hungary, residing at New York, in the county of New York and State of New York, have invented new and useful Improvements in Twine or Cord Cutters, of which the following is a specification.

This invention relates to improvements in twine or cord cutters wherein a supply of twine, in the form of a rolled ball, is supplied, the end being automatically advanced under the blade of a shear where it may be conveniently grasped.

The principal object of the invention is to provide an apparatus which will perform the foregoing functions in a satisfactory manner.

Another object is to provide an apparatus of this nature which is readily portable, but adapted to remain stationary under ordinary circumstances when placed upon any convenient level surface, and finally, to provide an apparatus of this class which is cheap to construct, comprised of few and simple parts and not readily liable to become disarranged.

These and other objects are attained by the novel construction and combination of parts hereafter described and shown in the accompanying drawing, forming a material part of this specification, and in which:—

Figure 1 is a perspective view of a twine cutter, made in accordance with the invention, and Fig. 2 is an enlarged vertical section of the same.

The invention comprises a hollow base 10, provided with a metallic frame 11 engaged upon its upper surface from which rises a standard 12, supporting a hollow twine holder 13, containing a ball of twine 14, a single strand 15 passing outward through an appropriate opening formed in its lower wall.

An arm 18, turnably mounted on a pivot pin 19 within the base of the apparatus, extends when erect, to a point above the surface of the frame 11, the arm having a transverse opening 20 through which the twine 15 passes, the arm also being formed with a horizontal central bore adapted to receive a plunger 22, having a curved upper surface 23 adapted to make contact with the twine 15 within the opening 20. The lower end of the plunger 22 extends rear-

wardly outward between the forked portions 24 of the arm 22, terminating in a curved end 25 engaged by the pin 26 with a lever 27, fulcrumed on the transverse pin 19 and having a depending lug 28 engaged by a pin 29 with a curved link 30, the upper end of which is connected by a pivot 31 with a bell-crank lever 33, fulcrumed on a transverse rod 35 fastened similarly to the rod 19 within the hollow base of the apparatus.

The bell-crank lever 33 has an oppositely disposed arm 36 to which is engaged one end of a coiled pull spring 38, the other end of the spring being secured to a stud 40 rigidly affixed to the interior wall of the base 10, the same having a normal tendency to draw the parts hitherto enumerated into the position indicated by the broken lines. Also engaged with the arm 36 of the bell-crank lever by a pivotal connection 42, is a vertical link 43, the same extending upward to the shear plate 45 to which it is attached by the pin 46. The shear is transversely mounted over the surface of the apparatus and is pivotally secured to a lug 47 formed with the frame 11, by means of the pin 48; the opposite end of the shear 45, which operates in the manner of a lever, is provided with an operating knob 50 by means of which the shear may be depressed and brought into operative engagement with a fixed shear 52 secured to the side of a transverse bar 53 formed with the frame 11. On top of the bar 53 is a lug 54 containing an opening through which the cord passes closely adjacent to the shear 45 to which is attached a projection 58, the same being bored vertically and containing a plunger 59, pressed normally downward by means of the coiled push spring 60, the reduced end 61 of the plunger extending downwardly through a cap 62 affixed to the lower end of the extension in such manner as to normally retain the plunger and spring 95 therein.

In operating the apparatus, pressure is applied to the knob 50, causing the shear to descend and cut off the cord. When the pressure is released, the spring 38 raises the pivoted shear 45 and through the system of links and levers employed, presses the plunger 22 against the cord in the passage 20, formed in the arm 18, binding it firmly therein. When the plunger 22 has risen so far as the passage 20 will admit, the arm is caused to swing upon the pin 19, in the di-

rection of the shear, causing the cord to advance thereunder, the plunger 61 being at that time raised. Further depression of the knob 50 not only brings the parts to their initial position, but clamps the cord 15 between the bar 53 and the plunger 61 closely adjacent, through the opening in the lug 54, thus extending a length convenient for the operator to grasp in the further operation of the apparatus.

Having thus described my invention, what I claim as new and desire to secure by Letters Patent is:—

1. A device of the class described, comprising a hollow base, a twine holder secured thereon, a pivoted arm hingedly connected to said base, said arm being bored to admit the passage of twine therethrough, a fixed cutter blade, a hinged cutter blade 20 coöperative therewith, a guide for the twine contiguous to said blades, means for clamping the twine adjacent to said guide when said hinged blade is depressed, means for raising said hinged blade, and means for projecting the cord past said hinged blade.

2. A device of the class described, comprising a hollow base, a twine holder secured thereto, an oscillating arm having an opening through which the twine passes,

means combined with said arm for clamping the cord therein, a fixed cutter blade, a cord guide arranged thereon contiguous to its edge, a hinged cutter blade, and means for normally maintaining said hinged cutter blade in a raised position, said raising means causing said arm to oscillate whereby the cord is carried forward.

3. A device of the class described, comprising a hollow rigid base having a surmounting frame, a cord carrier attached to said base and extending thereabove, a hollow arm oscillatably mounted in said hollow base, said arm having an opening through which the cord may pass, means for gripping the cord in said openings when said arm is caused to oscillate, a fixed blade, a twine guide mounted thereon, a hinged blade, means for depressing said hinged blade, means combined with said blade for clamping the cord contiguous to said cord guide, means for raising said hinged blade and means coöperative therewith adapted to clamp the cord within said arm and to cause said hollow arm to oscillate.

In testimony whereof I have signed my name to this specification.

FRANK KLINGA.
